UNITED STATES PATENT OFFICE.

JOSEPH M. ERTS, OF POUGHKEEPSIE, NEW YORK.

CAR-STARTER.

SPECIFICATION forming part of Letters Patent No. 359,013, dated March 8, 1887.

Application filed August 20, 1886. Serial No. 211,448. (No model.)

To all whom it may concern:

Be it known that I, JOSEPH M. ERTS, of the city of Poughkeepsie, in the county of Dutchess and State of New York, have invented a new and Improved Car-STARTER, of which the following is a full, clear, and exact description.

Reference is to be had to the accompanying drawings, forming a part of this specification, in which similar letters of reference indicate corresponding parts in all the figures.

Figure 1 is a plan view of the under side of a street-car having my invention applied thereto, the car being inverted. Fig. 2 is a broken longitudinal sectional elevation of the car in upright position, taken on line $x-x$ of Fig. 1. Fig. 3 is an end view of the car and starting mechanism. Fig. 4 is a detailed plan of the bottom of the car, showing an automatic safety detaching device to prevent injury to the starting mechanism. Fig. 5 is an enlarged side view of one form of safety detaching device. Fig. 6 is an enlarged inverted plan view of the car, showing a modification of the safety detaching mechanism. Fig. 7 is a sectional elevation of the same, the car being upright, taken on the line $y-y$ of Fig. 6; and Fig. 8 is an enlarged side view of the detaching device.

The invention will first be described in connection with the drawings, and then pointed out in the claims.

Upon the axle A of the car is placed loosely the two gear-wheels B C. These are adapted to be locked to revolve with the axle by the sliding clutches D E, placed upon the axle and controlled by levers F G at either end of the car, the said levers being attached to the rods H I, and the latter connected to the clutches, respectively, by the forked arms J K, so that by shifting the levers the rods may be turned and the arms J K caused to slide the clutches to engage or disengage the clutches of the wheels B C, as desired, to operate the starting mechanism.

The gear-wheel B meshes with a gear-wheel, L, secured upon the short shaft, L', journaled in hangers L² L³, depending from the bottom of the car. The gear-wheel C meshes with a gear-wheel, M, secured upon a short shaft, M', journaled in the hangers L⁴ and L⁵. The short shafts L' and M' are journaled in different planes, and are connected together by the two

pinions a b, secured upon the said shafts, respectively, so that the revolution of either shaft will communicate a reverse motion to the other.

To the shaft M' is secured the inner end of a coiled spring, N, the outer end of which is attached to the bottom of the car, so that the spring may be wound up by causing the shaft M' to revolve in the proper direction, which may be done by properly manipulating the levers F G, as next described. The spring N is by preference inclosed by the two side plates, c c, secured to the shaft M', so that the spring cannot get out of place or receive injury.

The operation is as follows: The car being drawn in the direction of the arrow, Fig. 2, both clutches D E being moved away from the clutches of the gear-wheels B C, the axle A and said clutches D E revolve independently of the starting mechanism. Now, when the car is to be stopped, lever F is to be moved to the left to engage clutch D with the clutch of the gear-wheel B. This will cause gear-wheel B to revolve with the axle, which motion will cause the short shafts M' L' to revolve in the proper direction to wind up the spring N. The car having been brought to a standstill, lever G will be moved to the right to engage clutch E with the clutch of the gear-wheel C. This done, and the car ready to start again, the lever F will be moved to disengage clutch D from the clutch of the gear-wheel B, whereupon the tension of the spring N will exert a forward motion to the axle through the shaft M', gear-wheels M C, and clutch E, and assist in starting the car. When the car is reversed and drawn in the direction opposite to that indicated by the arrow in Fig. 2, the sequence of movements of the levers F G will be exactly reversed from that above described.

In case the brakeman should fail to detach the clutch D or E at the proper time, to avoid injury to the spring N, which would result from such neglect, I attach to the shafts L' M' automatic clutch-shifting devices O, for shifting the clutches on the axle out of engagement with the clutches on its wheels B C, thus releasing all strain, upon the springs. This automatic device consists of several circular disks or plates, m n o p q, Fig. 5, each of less diameter than the disk next to it. The disks are each formed with a projection, r, that stands in the

same plane with the disk, and with a projection, r' , that stands at right angles to the plane of the disk. The disk q is made fast to the shaft, while the other disks are loose thereon, 5 and the largest disk, m , in Fig. 5, is formed with a cam, m' , at the outer edge to strike against a flange, e' , upon the clutch, so that by the revolution of the plate m the cam will move the sliding clutch out of engagement with its 10 corresponding clutch on the cog-wheel. The plates or disks $m\ n\ o\ p\ q$, Fig. 5, are arranged so that the shaft may revolve independently 15 of the disk m a number of revolutions, the number corresponding with the number of disks, as each disk must make a complete revolution before it revolves the next larger disk.

It will be understood that the whole action 20 of the safety device is derived from the plate q , which revolves with the shaft until its projection r strikes the projection r' of the disk p . These two disks will now revolve together until the projection r of the disk p strikes the projection r' of the disk o , when the latter 25 will revolve and in turn revolve plate n , which in turn will revolve plate m and cause the cam m' to act upon the clutch and disengage it from the clutch on the cog-wheel, so that the starting mechanism will thereby be thrown 30 entirely out of action, and all danger of injury to the spring N and other parts of the starting mechanism avoided.

In place of the cam m' in each of the devices 35 for shifting the clutch, I may form the plates q , which are loose upon the auxiliary shafts, with arms q' . (See Fig. 8.) To these arms I attach the central arm, s , of double bell-crank lever S by the rods $s'\ s'$. (See Figs. 6 and 7.) The double bell-crank lever S is pivoted upon 40 the lower end of a stud, S' , attached to the bottom of the car. The arm s^2 of this double lever is connected by rod t and arm t' to the rod H , while the arm s^3 is connected by the rod t^2 and arm t^3 to the rod I . Constructed 45 in this manner, when the car is not stopped in time, the auxiliary shaft will make as many revolutions as there are disks, or until the projection r' of the outer disk, m , (which revolves with the shaft,) causes the disk q to revolve. 50 When this latter disk is caused to turn, the arm q' turns the double bell-crank S on its pivot and causes it to turn the rods $H\ I$, which

will cause them, through their connections with the clutches $D\ E$, to slide said clutches away from the clutches on the cog-wheels, and thus entirely release the starting mechanism, so it is thrown entirely out of action automatically, and thus saved from injury.

If the car should run with unusual speed, I can attach a friction-clutch to the clutches $D\ E$, so that if the spring should wind up before the car stops the friction-clutches will relieve the spring.

Having thus fully described my invention, I claim as new and desire to secure by Letters Patent—

1. The axle A of the car, provided with the sliding clutches $D\ E$ and loose gear-wheels $B\ C$, each formed with a clutch to receive the teeth of the clutches $D\ E$, in combination with two auxiliary shafts, $L'\ M'$, journaled in different planes in fixed bearing, the spring N on shaft M' , the gear-wheels $L\ M$, fixed upon the auxiliary shafts $L'\ M'$, respectively, the pinions $a\ b$, connecting the said two auxiliary shafts, and means, substantially as described, for shifting the clutches $D\ E$ on the axle A from the platforms of the car, substantially as described.

2. The sliding clutches $D\ E$ on the axle A , formed with flanges, the auxiliary shafts $L'\ M'$, geared together and provided, respectively, with gear-wheels $L\ M$, the shaft M' being provided with the spring N , in combination with the clutch-wheel $B\ C$, loose on the axle A , and the automatic devices O , attached to the auxiliary shaft $L'\ M'$ and revolving therewith, for shifting the clutches $D\ E$ on the shaft A , substantially as and for the purpose described.

3. The automatic clutch-shifting device O , consisting of plates $n\ o\ p\ q$, formed with horizontal and radial arms $r\ r'$, and placed loosely upon the auxiliary shaft, the disk m , made fast to said shaft, and the disk q , provided with the arm q' , in combination with bell-crank lever S , rods $H\ I$, connected by the sliding clutches and the connecting-rods $t\ t^2\ s'$, and the arms $t^1\ t^3$, substantially as and for the purposes described.

JOSEPH M. ERTS.
